UNITED STATES PATENT OFFICE.

HENRY O. SCHIMDT, OF NEW YORK, N. Y., ASSIGNOR TO THE LANDERS,
FRARY & CLARK, OF NEW BRITAIN, CONNECTICUT.

DESIGN FOR A FERRULE.

SPECIFICATION forming part of Design No. 25,267, dated March 24, 1896.

Application filed February 20, 1896. Serial No. 580,134. Term of patent 7 years.

To all whom it may concern:

Be it known that I, HENRY O. SCHIMDT, a citizen of the United States, residing at New York, in the county of New York and State of New York, have invented and produced a new and original Design for a Ferrule, of which the following is a specification, reference being had to the accompanying drawings, in which—

10 Figures 1 and 2 are side elevations of a ferrule for cutlery-handles, showing my design. Fig. 3 is an end view thereof.

The ferrule is of an oval form in cross-section or end view and is ornamented by a plain 15 narrow bead near each end and two intermediate bands of scroll leaflets.

The plain narrow beads 4 are arranged at a

short distance from each end of the ferrule, as shown. Upon the open field or plain ground between these beads 4 there are two other 20 bands 5 at equal distances from the longitudinal middle of the ferrule, said bands being composed of curved leaflets abutting against each other, as shown. These bands are placed somewhat nearer to the beads 4 than they are 25 to each other, thus leaving a wide open field at the middle portion.

What I claim is—

The design for a ferrule substantially as herein shown and described.

HENRY O. SCHIMDT.
